TIMED AUTOMATIC TUNING DEVICE FOR
RADIO RECEIVERS

James M. Davenport, Detroit, Mich.

Application January 26, 1938, Serial No. 186,947

3 Claims. (Cl. 200—38)

My invention relates to a new and useful improvement in a timed automatic tuning device for radio receivers in which there is provided means for automatically, at predetermined times, operating the electric automatic tuning mechanism of the radio receiver set and also means for determining, selectively, beforehand, the definite times of operation.

Another object of the invention is the provision of a device which will be used in combination with a radio receiver having an electric automatic tuning mechanism and provided with operating members which may be set for operating the tuning mechanism at predetermined times, automatically.

Another object of the invention is the provision, with a radio receiver having an automatic tuning mechanism, of a structure driven at a predetermined speed and provided with separable actuating members which may be set to operate the tuning mechanism at predetermined positions as the device is driven to these positions.

Another object of the invention is the provision of a mechanism adapted for use with a radio receiver having an automatic tuning mechanism whereby it becomes possible for the operator to set a mechanism in position for operating the tuning mechanism to tune selected stations in at selected times over a period of time.

Another object of the invention is the provision of a mechanism of this class in which the actuating device will automatically be moved to non-setting position after it has operated the tuning mechanism subsequently to having been set.

Another object of the invention is the provision of a mechanism of this class which will be simple in structure, economical of manufacture, durable, compact, easily and quickly operated and highly efficient in use.

Other objects will appear hereinafter.

The invention consists in the combination and arrangement of parts hereinafter described and claimed.

The invention will be best understood by a reference to the accompanying drawings which form a part of this specification, and in which,

Fig. 1 is a front elevational view of a radio receiver showing the invention applied.

Fig. 2 is a front elevation view of the invention slightly enlarged with parts broken away.

Fig. 3 is a fragmentary, sectional view taken on line 3—3 of Fig. 2.

Fig. 4 is a fragmentary, sectional view taken on line 4—4 of Fig. 2.

Fig. 5 is a sectional view taken on line 5—5 of Fig. 4.

Fig. 6 is a view similar to Fig. 5 showing the invention in another position.

Fig. 7 is a sectional view taken on line 7—7 of Fig. 4.

Fig. 8 is a front elevational view of a modified form of the invention with parts broken away and parts shown in section.

Fig. 9 is a fragmentary, sectional view taken on line 9—9 of Fig. 8.

Fig. 10 is a sectional view taken on line 10—10 of Fig. 8.

Fig. 11 is a sectional view taken on line 11—11 of Fig. 8.

Fig. 12 is a sectional view taken on line 12—12 of Fig. 11.

The invention is adapted for use on a radio receiving set and in the specification this structure will be referred to as a radio.

The invention is mounted on the front panel of the radio 19 and is intended to operate the automatic tuning mechanism which is constructed as a part of the radio. This automatic tuning mechanism forms of itself no part of the present invention and is not shown in detail, only such parts of the same being illustrated as may be necessary for an understanding of the operation of the present invention.

Mounted on a suitable support 20 behind the front panel 21 of the radio is an electric clock mechanism 22 adapted for rotating the shaft 23, this driving mechanism 22 being so timed as to effect a rotation of the shaft 23 once in twelve hours. To operate the automatic tuning mechanism it is necessary to close a predetermined circuit in order that the radio receiver may be tuned to that station so that the radio is provided with one of these circuits for each station that it is adapted to automatically tune into. In

Fig. 3 I have shown the radio equipped to operate at a capacity of four stations and for each station there is provided an electric cable 24, each of these cables connecting to the insulation bus bar 25 by means of a rivet or bolt 26, the head of which serves as a contact. Mounted in spaced relation to the member 25 is a metallic plate 27 which is connected to the side wire 28. Mounted

at one end to the bar 27 and positioned opposite each of the contact rivets or bolts 26, is a resilient contact member 29 which is formed substantially V-shaped as shown in Fig. 4 and the free end of which projects through a slot 30 formed in the plate or bar 27. Mounted

at one end to the bar 27 and positioned opposite each of the contact rivets or bolts 26, is a resilient contact member 29 which is formed substantially V-shaped as shown in Fig. 4 and the free end of which projects through a slot 30 formed in the plate or bar 27. The free end of this switch blade or contact member 29 is angu-

larly turned as shown in Fig. 4 and normally is in the dotted line position shown in Fig. 4 out of engagement with the contact 26. When pressed into the full line position shown in Fig. 4, the member 29 will contact the contact member 26 and close connection between the feed wire 28 and the individual cables 24 depending upon which of the switch blades has been pressed into circuit-closing position. As soon as one of these switch blades is pressed into the full line position shown in Fig. 4 so as to close the circuit, the tuning mechanism will be operated to tune the radio into the particular station selected.

Fixedly mounted on the shaft 23 so as to rotate therewith are the discs 31 and 32, these discs making one complete revolution every twelve hours. The radio programs are generally arranged to begin on the quarter hour and the invention is constructed to accord with this arrangement. I have determined on the face of the disc 32 radii. These radii being axially spaced to correspond to the fifteen minute period and on each radius so determined, I have mounted a plurality of operating plungers. The innermost rows of plungers is used for a different purpose than the outer rows of plungers, although the structural details are the same. The inner rows of plungers may be termed the radio control buttons or plungers and the outer rows may be termed the selective station plungers or buttons. Formed in the disc 32 are the openings 33 in which is slidably positioned the plunger head or cup-shaped member 34 which has a centrally extending sleeve 35 projecting inwardly from its base and into which a reduced threaded end 36 of the stem 37 of insulation is threaded. This stem 37 slidably projects through an opening 38 formed in the disc 31. Embracing this stem 37 and entering at one end of the cup-shaped head 34 and engaging at its opposite end the face of the disc 31, is a coiled spring 39. The stem 37 is provided on its inner end with a head 40 and between the head 40 and the medial line of the stem this stem 37 is cut away to provide a shoulder 41. Mounted at one end on the disc 31 is a spring catch 42 having the angularly turned end 43 adapted to engage the periphery of the stem 37. Secured to and projecting outwardly beyond this spring catch 42 is a releasing arm 44. Mounted on the outer face of the bar 27 is a plate 45 having the outwardly directed V-shaped flange 46. This flange 46 is mounted on the plate 27 by means of a screw 47 projected through the slot 48 so that the plate 45 may be adjusted relatively to the plate 27 within the limits of the slot 48, the flange 46 being insulation.

The construction is such that when the stem 37 is pressed inwardly from the position shown in Fig. 6 to the position shown in Figs. 4 and 5, the angularly turned portion 43 of the catch 42 will engage behind the shoulder 41 and retain this stem in its inwardly thrust position. Each of the four outer rows is intended to operate the mechanism for tuning in a particular station. For instance, the plungers in the outer row, which may be termed A, would serve to operate the automatic selective tuning mechanism for a particular station. The row B for another station, the row C for another station and the row D for still another station. The individual buttons in the row A will determine at what time of the day the station represented by that row shall be tuned in and this applies also to the other rows B, C, and D. Consequently, if it were

intended to have the tuning mechanism of a certain station operated for instance at one-thirty, the plunger in the proper row on the radial line corresponding to time of one-thirty would be pressed inwardly against the compression of the spring 39 and the angularly turned end 43 of the catch 42 would retain this plunger in its inwardly pressed position. As this plunger would arrive at the switch blade 29 controlling the circuit to the tuning mechanism for that particular station the head 40 would ride over the angularly turned end of the switch blade 29 and force it inwardly from the dotted line to the full line position as shown in Fig. 4 and close the circuit through the connecting cable 24. As this disc 32 would continue to rotate, the head 40 would ride over the angularly turned end of the switch blade 29 and force it inwardly from the dotted line to the full line position as shown in Fig. 4 and close the circuit through the connecting cable 24. As the disc 32 would continue to rotate, the head 40 would ride off of the angularly turned end of the switch blade 29 so that the switch blade 29 would spring into the dotted line position shown in Fig. 4. This, however, would not stop the operation of the radio and it would continue tuned into the station selected. As the disc 32 would continue to rotate, the arm 44 would ride along the inner face of the V-shaped flange 46 and the arm 44 would be pressed so as to flex the catch member 42 backwardly and release the angularly turned portion 43 from engagement with the shoulder 41 whereupon the plunger 37 would, in respect to the pressure of the spring 39, return to its inoperative position as shown in Fig. 6. In this position the angularly turned portion 43 of the catch 42 would, at its end, engage the flat surface of the head 40 so as to flex the member 42 backwardly and move the arm 44 out of the position at which it would engage the V-shaped flanges 46 at subsequent locations. In this way the circuit may be closed at predetermined times to operate the tuning device for selecting predetermined stations.

It is obvious that once the device has been operated the station selected will continue to be tuned in until another operation is accomplished.

In setting the device for a certain time, the operator, in addition to pressing in the desired plungers in the four outer rows, would also press inwardly the plunger in the inner row on the line indicating the time desired to have the radio go into operation and also press inwardly the plunger in the inner row on the radial line indicating the time at which it is desired that the radio should cease operating. When the plunger in the innermost row is pressed inwardly, it is held in its inwardly pressed position as already described.

Mounted on the supporting body 20 and projecting outwardly therefrom is a stud 49 on which is mounted a metallic band 50 having a plurality of axially directed arms 51 extending outwardly therefrom and outwardly offset from the stud 49 as shown in Fig. 11. An electric cable 52 is connected in contact with the band 50. Rotatably mounted on the end of the stud 49 is a cup-shaped hub 53 projecting outwardly from which, in spaced relation, are the spokes 54. Mounted on the inner face of the hub 53, in spaced relation to correspond to the spacing of the arms 51, are contact plates 55 connected to the electric wire 56. Recesses 57 are formed on the inner face of the hub 53 between these contact plates 55. The construction is such that

when the hub 53 is turned into the position shown in Fig. 12 so that the contact plates 55 engage the arms 51, the circuit to the radio would be closed. When the hub 53 is rotated so that the 5 arms 51 are out of engagement with the plates 55, the circuit to the radio would be open and the arms 51 would then rest in the recesses 57. These arms 51 are resilient and a snap action is thus provided. This structure serves as the 10 switch for turning the radio on and turning it off. As the disc 32 rotates, the plunger in the innermost row which has been pressed inwardly will engage one of the spokes 54 and rock or rotate the hub 53 to close the circuit to the radio 15 and turn it on. As the disc 32 continues to rotate after the radio has been turned on by a rotating of the hub 53, the outwardly extending arm 44 on the plunger in the innermost row will engage the V-shaped flange 46 and the plunger 20 will be released to move to inoperative position so that it will not continue to rotate the hub 53. The succeeding plunger in the innermost row, which has been pressed inwardly, will serve to rotate the hub 53 to turn the radio off 25 so that it thus becomes possible to set the mechanism to automatically turn the radio on and off at predetermined times. Consequently, when the program which has been automatically turned on has finished, the radio will be automatically 30 turned off also.

In Fig. 8 I have shown a slightly modified form of construction which is particularly adaptable for use on radios of height such as the cabinet type. Mounted on the face of the radio is a 35 frame embodying the side rails or tracks 60 and 61, one part of which forms a track structure the remainder of which forms the front plates 62 and 63, respectively. Positioned between these tracks 60 and 61 is a plate 64 having the outwardly projecting brackets 65 at opposite edges thereof, each carrying a roller 66 engaging in a groove 67 formed on the inner face of the track members 60 and 61. Mounted on this board or plate 64, in a vertical row, is a plurality of plungers 71' each carrying a head or cap 34' and each in alignment with a switch blade 29'. The function and operation of these plungers 37', cooperating with the switch blades 29', is the same as the corresponding parts described and shown 50 in the form illustrated in Fig. 2 and Fig. 3. The plate or board 64 moves vertically, the operation of which will be presently described. On the opposite side of the plate or board 64 is a vertical row of plungers 37'' corresponding to the 55 plungers 37 on the innermost row in the construction shown in Fig. 2. Each of these plungers carries on its outer end a head 34'' and is adapted to operate the control switch through engagement with the spokes 54'.

Formed in the board or plate 64 is an elongated, vertical extending slot 68 along the margins of which are graduations corresponding to the hour sections. Rotatably mounted on brackets 69 projecting inwardly from the board 64 65 is a shaft 70 carrying a drum 71 on the face of which is deposited a plurality of circumferentially spaced rows of spaced numbers corresponding to the hours. In Fig. 8 these hours extend from one to seven. By rotating the knurled wheel 70 72 which is fixedly mounted on the shaft, the drum 71 may be rotated to bring into registration with the slot 68 a different sequence of numbers. On the member 63 is displayed an indicator such as the arrow 73.

Secured to and depending from the plate 64

is a rack bar 74 adapted to mesh with the pinion 75 which is mounted on the shaft 76 in axial slideable relation thereto but so as to rotate therewith. This shaft 76 projects outwardly from the clock mechanism 77 which serves as a governor. 5 A spring 78 embraces the shaft 76 and presses at one end against the face of the clock mechanism 77 and at the opposite end against the pinion 75 to normally maintain this pinion 75 thrust outwardly into position for meshing with the rack 10 bar 74, an outwardly projecting pin 79 limiting the outward movement of this pinion 75. Projecting outwardly from the outer face of the pinion is a head 80 which is slidable on the shaft 76. By pressing inwardly on the head 80, the 15 pinion may be moved inwardly against the compression of the spring 78 out of mesh with the rack bar 74. When this is done the board or plate 64 may be elevated to the desired position. For instance, if it should be two o'clock at the 20 time the mechanism is set, the board 64 would be elevated until the arrow 73 registered with the hour two indicated on the board or plate 64. The inward pressure on the pinion 75 would then be released so that this pinion would then 25 mesh with the rack bar 74 and the clock mechanism 77 would permit the board or plate 64 downwardly in response to gravity at such a rate that the space between the various numbers would be traversed in the times indicated. As 30 the plate travels downwardly and the plungers 37', which may have been pressed inwardly, ride over the aligning switch 29', the circuit actuating the tuning mechanism for tuning in that particular station would be closed, the switch 35 blade 29' contacting a contact 26' connected to the cable 24' and mounted on the bar 25'. The plungers 27'' pressed inwardly would operate the control switch by engaging one of the spokes 54' and rotating the hub 53', the operation being the same as already described. This type of structure is adapted for accomplishing the results attained by the use of the preferred form of structure. It may, however, be adjusted manually as to time and the hours of operation are, 40 of course limited. The various rows will, of course, be indicated as to the stations to which they are related and it is believed obvious that when desired the mechanism may be operated manually in the customary manner. 50

As shown in Fig. 7 the bar 25' is mounted with a bolt 99 projected through the slot 97 so that this bar may be positioned for effecting proper alignment.

It is believed that with the structure illustrated, 55 I have provided a simple and effective means for attaining the results mentioned and that a compact, durable structure is thus provided.

While I have illustrated and described the preferred forms of constructions, I do not wish to 60 limit myself to the precise details of the structures illustrated, but desire to avail myself of such variations and modifications as may come within the scope of the appended claims.

What I claim as new is:

1. A device of the class described adapted for use with a radio receiver having an electric automatic tuning mechanism and provided with switch closing members for operating the same, a movable supporting body movable at a predetermined rate of speed; a second supporting body movable in unison with and spaced from said first mentioned supporting body; a plurality of plungers projecting through said bodies and movable inwardly to operative position and outwardly 70 75

to inoperative position; a spring for normally retaining said plunger moved outwardly to inoperative position; a shoulder on each of said plungers; spring members carried on said second mentioned supporting body and engageable behind a shoulder of a plunger upon inward movement of the same for retaining the same in operative position; a stationary body; a stop on said body; and means projecting outwardly from said second mentioned supporting body engageable with said stop, upon movement of said supporting body to a predetermined position with a plunger in operative position, for releasing said plunger for movement to inoperative position.

15. 2. A device of the class described adapted for use with a radio receiver having an electric automatic tuning mechanism and provided with switch closing members for operating the same, a movable supporting body movable at a predetermined rate of speed; a second supporting body movable in unison with and spaced from said first mentioned supporting body; a plurality of plungers projecting through said bodies and movable inwardly to operative position and outwardly to inoperative position; a spring for normally retaining said plunger moved outwardly to inoperative position; a shoulder on each of said plungers; spring members carried on said second mentioned supporting body and engageable behind a shoulder of a plunger upon inward movement of the same for retaining the same in operative position; a stationary body; a stop on said body; and means projecting outwardly from said second mentioned supporting body engageable with said stop, upon movement of said supporting body to a predetermined position with a plunger in operative posi-

tion, for releasing said plunger for movement to inoperative position; a control switch; and means connected with said control switch engageable with said outwardly projecting releasing means for operating said control switch periodically upon the movement of said supporting bodies to predetermined positions.

3. A device of the class described, adapted for use in a radio receiver, having an electric automatic tuning mechanism and provided with switch-closing members for operating the same; a movable supporting body, movable at a predetermined rate of speed; a second supporting body spaced from said first mentioned supporting body and movable in unison therewith; a plurality of 15 plungers carried by and projecting through said supporting members and movable inwardly to operative position and outwardly to inoperative position; releasable means engaging each of said plungers upon its movement inwardly to operative 20 position for retaining the same in operative position; a plurality of switches, each of said plungers upon movement of said supporting members to predetermined positions, engaging a switch and moving the same to closed position; a control 25 switch, embodying a rotatable operating mechanism adapted upon rotation to a predetermined position for closing the switch and rotation to another predetermined position for opening the switch; a plurality of spaced arms projecting outwardly from said rotatable mechanism and engageable with an operative plunger, the plunger engaged therewith, effecting a rotation of said rotatable mechanism upon movement on said supporting members.

JAMES M. DAVENPORT.
